UNITED STATES PATENT OFFICE.

CHARLES ELKIN, OF NEW YORK, N. Y.

PIPE.

No. 818,819.

Specification of Letters Patent.

Patented April 24, 1906.

Application filed July 12, 1905. Serial No. 269,280.

To all whom it may concern:

Be it known that I, CHARLES ELKIN, a citizen of the United States, residing at New York, in the county of New York and State of New York, have invented or discovered certain new and useful Improvements in Pipes, of which the following is a specification, reference being had therein to the accompanying drawings.

This invention has for its object to provide a tobacco-smoking pipe of such construction that the smoke drawn from the bowl of the pipe will be well cooled by the time it reaches the mouth of the smoker, so that the disagreeable and injurious effects resulting from the impact of hot smoke against the tongue or other parts of the mouth of the smoker will be altogether avoided.

The invention comprises certain improvements on the pipe covered by United States Patent No. 767,804, granted August 15, 1904.

The present improved pipe preferably comprises three or more smoke-cooling chambers, arranged, as hereinafter set forth, in the smoke-passage of the pipe and each of which chambers has a contracted inlet, so that a cross-sectional area of each of said chambers is of very much greater extent than the area of the inlet thereto, and thus as the smoke is drawn to each of the cooling-chambers it will be cooled by rarefaction, as also by a more or less whirling or tumbling effect to which it will be subjected in each of the said chambers.

In the accompanying drawings, Figure 1 is a sectional view of a pipe embodying the present invention, and Fig. 2 illustrates a modification thereof.

Referring to the drawings, *a* denotes the bowl of the pipe, in the stem portion *a'* of which is formed the chamber *b*, communicating by a contracted passage-way or duct *c* with the chamber of the bowl. The chamber *b* is preferably a straight bore, such as can be made with an ordinary drill or bit, and the passage-way or duct *c*, which intersects the chamber *b* at an acute angle, is preferably so inclined and located that it can be made by a drill inserted from the upper or outer end of the chamber *b*. In other words, the extended line of the passage-way *c* will be within the walls of the upper or outer end of the chamber *b*.

The stem proper, *l*, of the pipe has a contracted inlet *d*, opening into the upwardly-expanding smoke-cooling or rarefaction chamber *e*, which communicates with the passage-

way *f*, leading to the final smoke-cooling or rarefaction chamber *g*, having a contracted inlet *h*. The walls of the chamber *e* are preferably made as thin as is practicable, so that the rarefied smoke in said chamber will be cooled as much as possible from the cooler outside air, and thus these cooler walls will act as a condenser and a deposit of injurious substances, comprising percentages of nicotin and oxalic acid, will be formed on said walls and will run down into the chamber *b*, from which it may be readily removed by taking out the pipe-stem *l*. The final smoke-cooling chamber *g* is preferably formed in a removable cap provided at its upper side only with smoke-exit holes *i*, and in this respect the present pipe is like that covered by United States Patent No. 767,804, above referred to, although the form of this chamber *g*, as also the form of the tip *j* to which the cap *i*, screwed or otherwise attached, may be somewhat varied, although the tapered extreme end of said tip is preferred.

The stem of the pipe is preferably provided just forward of its mouth piece or tip with an air-inlet hole *k*, which is sufficiently near the mouthpiece, so that it may be covered by the lip of the smoker, if desired, or may be left open for the entrance of a small amount of air to cool the smoke. The stem of the pipe is also preferably provided at its lower portion, above the chamber *e*, with a second air-inlet hole *m*, which, at the pleasure of the smoker, may be left open for the entrance of air to cool the smoke or may be covered by the finger of the smoker, as is deemed preferable. In use, however, it will be found advantageous to leave one, or both, of the air-inlet holes *k m* open for the ingress of a small quantity of air to cool and dilute the smoke, and thus augment the cooling effects produced by the three rarefaction or cooling chambers *b*, *e*, and *g*. The chamber *b* also serves as a trap, as will also the chamber *g*, so that nicotin and other injurious deposits from the smoke will be safely excluded from the mouth of the smoker. The chamber *g*, having smoke-exit orifices only in its upper wall, will receive little or no saliva from the mouth of the smoker, and thus clogging of the smoke-passage in the pipe-stem from this cause will be avoided. The chamber *e* is upwardly expanding or of inverted conical form.

In the modified form of the invention illustrated in Fig. 2 an additional cooling or rarefying chamber is provided by the stem-sec-

- tion *o* between the chamber *b* in the stem part of the bowl and the chamber *e* in the pipe-stem proper, *l*, this additional cooling or rarefying chamber preferably comprising the conical or tapered part *p* and the globular part *q*. Still other cooling or rarefying chambers might be added, if desired, as will be understood, without departing from the essence of the invention.
- 10 In the use of the pipe constructed with three or more rarefaction or cooling chambers, as herein described, the hot smoke, which when it first issues from the chamber of the bowl is at a temperature of approximately 400° Fahrenheit, will be, according to the temperature of the outside atmosphere, so cooled that when it finally issues into the mouth of the smoker it will be reduced to a temperature near or below 90°
- 15 Fahrenheit, and thus the injurious and disagreeable effects resulting from the reception of hot smoke into the mouth of the smoker, and particularly against the tongue, will be altogether avoided. This result is due
- 20 partly to the rarefaction of the smoke in each of the cooling-chambers, in which most of it is momentarily detained and more or less whirled about, and partly due to the cooling effect of the air entering one or both of the
- 25 inlet orifices or holes *k m*.

Having thus described my invention, I claim and desire to secure by Letters Patent—

1. A pipe having the stem of its bowl portion provided with a smoke-cooling straight-bore chamber *b* and with a contracted passage-way or duct *c* intersecting said chamber *b* above the bottom of the latter, said pipe having a stem in which is formed the upwardly-expanding or conical chamber *e* with a contracted inlet, and the mouthpiece of said stem having the chamber *g* with smoke-exit orifices at its top only.
2. A pipe provided in the smoke passage-way between the chamber of the bowl and the smoke-discharge outlet at the mouthpiece with three or more smoke-cooling or rarefaction chambers each having a contracted inlet, one of said chambers being formed in the stem portion of said bowl, one, at least, of said chambers being formed in the stem proper of the pipe, and one at the mouthpiece or smoke-exit end of the pipe.
3. A pipe provided in the smoke passage-way between the chamber of the bowl and the smoke-discharge outlet at the mouthpiece with three or more smoke-cooling or

rarefaction chambers each having a contracted inlet, one of said chambers being formed in the stem portion of said bowl, one, at least, of said chambers being formed in the stem proper of the pipe, and one at the mouthpiece or smoke-exit end of the pipe, the stem of said pipe being provided at its lower part or adjacent the said bowl with an air-inlet hole.

4. A pipe provided in the smoke passage-way between the chamber of the bowl and the smoke-discharge outlet at the mouthpiece with three or more smoke-cooling or rarefaction chambers each having a contracted inlet, one of said chambers being formed in the stem portion of the bowl, one, at least, of said chambers being formed in the stem proper of the pipe, and one at the mouthpiece or smoke-exit end of the pipe, the stem of said pipe being provided at its lower part or adjacent the said bowl with an air-inlet hole, and said stem having also an air-inlet hole adjacent the said mouthpiece.

5. A pipe having the stem of its bowl portion provided with a smoke-cooling straight-bore chamber *b* and with a contracted passage-way or duct *c* intersecting said chamber *b* above the bottom of the latter, said pipe having a stem in which is formed the upwardly-expanding or conical chamber *e* with a contracted inlet, and the mouthpiece of said stem having the chamber *g* with smoke-exit orifices at its top only and the said stem being provided, adjacent said mouthpiece, with an air-inlet hole *k*.

6. A pipe having the stem of its bowl portion provided with a smoke-cooling straight-bore chamber *b* and with a contracted passage-way or duct *c* intersecting said chamber *b* above the bottom of the latter, said pipe having a stem in which is formed the upwardly-expanding or conical chamber *e* with a contracted inlet, and the mouthpiece of said stem having the chamber *g* with smoke-exit orifices at its top only, and the said stem being provided, adjacent said mouthpiece, with an air-inlet hole *k*, and said stem having also the air-inlet hole *m* adjacent the bowl portion of the pipe.

In testimony whereof I affix my signature in presence of two witnesses.

CHAS. ELKIN.
